UNITED STATES PATENT OFFICE.

JOSEPH M. ADAMS, OF MELROSE, MASSACHUSETTS.

SNAP-FASTENER.

No. 885,419.

Specification of Letters Patent. Patented April 21, 1908.

Application filed May 8, 1907. Serial No. 372,518.

To all whom it may concern:

Be it known that I, JOSEPH M. ADAMS, citizen of the United States, residing at Melrose, in the county of Middlesex and State 5 of Massachusetts, have invented certain new and useful Improvements in Snap-Fasteners, of which the following is a specification.

The present invention relates to improvements in snap fasteners and has for its object 10 to design a fastener of this type in which the two members are securely locked against becoming accidentally detached and can only be separated by first moving one of them laterally against the direction of the 15 pull exerted thereon by the two sections of the garment or other members being connected by the fastener.

The invention also aims to provide a snap fastener in which both the socket and key 20 have a flattened formation and are prevented from having any relative rotary movement, thereby eliminating the common tendency of the garments to gap due to this cause.

25 For a full description of the invention and the merits thereof and also to acquire a knowledge of the details of construction and the means for effecting the result, reference is to be had to the following description and 30 accompanying drawings, in which:

Figure 1 is a longitudinal sectional view showing a snap fastener applied. Fig. 2 is a bottom plan view of the socket member. Fig. 3 is a top plan view of the same. Fig. 4 35 is a detached perspective of the key plate.

Corresponding and like parts are referred to in the following description and indicated in all the views of the drawings by the same reference characters.

40 In general the snap fastener comprises a socket plate 1 provided with a socket 2 and designed to be attached to one of the members being connected, and a key plate 3 carrying a key 4 having an interlocking connection with the socket 2 and designed to be secured to the opposite member being connected. The mouth of the socket 2 has the sides thereof rounded to guide the key 4 into the base or body portion of the socket 45 which has a flattened formation, being contracted laterally and elongated longitudinally. Cuts or incisions 5 are formed in opposite ends of the socket 2 at points adjacent the socket plate 1, one of the incisions 55 receiving a laterally disposed spring arm 6, while the opposite incision permits the key

to engage a portion of the socket plate 1 forming a square shoulder 7, the socket projecting over the said shoulder. The edges of the socket plate 1 are returned upon themselves rearwardly to form the annular channel 8 receiving the curved ends of a piece of spring wire 9, an intermediate portion of which is crimped at 10, the said crimped portion being formed with a flattened loop 65 one side of which constitutes the before mentioned spring arm 6 received within one of the incisions 5.

The key 4 which is preferably located centrally of the key plate 3 has a flattened formation corresponding to the socket 2 and when in position within the latter the key plate is locked against any rotary movement relative to the socket plate. The nose of the key 4 is inclined in opposite directions in the 70 usual manner while the base of the key is provided at its opposite ends with notches forming the approximately square shoulders 11 engaging respectively the spring arm 6 and the shoulder 7 of the socket plate. The length 75 of the socket 2 is slightly greater than the length of the key 4 so that the latter is permitted to have a limited amount of backward and forward play when in position within the socket. The two members are 80 pressed together in the usual manner; one of the shoulders 11 upon the key, being engaged by the spring 6 while the opposite shoulder engages the square shoulder 7 of the socket. It may here be mentioned that 85 when applying the plates to the members designed to be connected by the fastener the socket plate 1 is so positioned that the square shoulder 7 is on the side toward which the pull is exerted by the key. It 90 will thus be apparent that the tendency of the members being connected to pull apart draws the square shoulders 11 and 7 of the key and socket respectively into a firm engagement with each other, and that when 95 in this position the said shoulders have an interlocking connection which prevents the socket plate and the key plate from being separated. Attention may also be directed to the fact that the action of the spring 6 is 100 such as to normally hold the before mentioned shoulders in engagement with each other. In order to detach the two plates it is necessary to move one of them laterally 105 against the pull of the members being connected by the fastener and against the action of the spring 6 until the square shoulder 110

11 of the key is disengaged from the shoulder 7 of the socket, whereupon the two plates may be opened apart. It will thus be seen that the motion required for un-snapping the members is a simple, natural, and quick one, being similar to that required for detaching a hook from an eye. The two plates 1 and 3 may be applied to the sections of the garment in any suitable manner and for this purpose are shown in the present instance as provided with the openings 12 which admit of their being sewed to the garment.

Having thus described the invention, what is claimed as new is:

- 15 1. In a fastener, the combination of a socket plate provided with a socket having a shoulder on one side thereof and an incision in the opposite side, a spring arm carried by the socket plate and received by the said incision, and a key plate carrying a key designed to be received within the socket and having opposite sides thereof notched, the said key being movable laterally within the socket to permit one of the notches to be moved into and out of engagement with the shoulder of the socket, the opposite notch being yieldingly engaged by the spring arm.
- 20 2. In a fastener, the combination of a socket plate carrying a flattened socket having an incision in each end thereof, one of the incisions being located adjacent a portion of the socket plate constituting a shoulder, a

key plate carrying a flattened key having opposite ends thereof notched, the said key being movable within the socket to permit one of the notches to be moved into or out of engagement with the before mentioned shoulder, and a spring arm carried by the socket plate and received within one of the incisions of the socket to yieldingly engage the opposite notch of the key.

3. In a fastener, the combination of a socket plate, having the edges thereof turned, the said socket plate being formed with a socket having a shoulder at one end thereof and an incision at the opposite end, a key plate formed with a key designed to be received loosely within the socket and having opposite sides thereof notched, the movement of the key within the socket permitting one of the notches to be thrown into and out of engagement with the shoulder, and a spring strip having end portions thereof curved and engaging the returned edges of the socket plate, an intermediate portion of the spring strip being crimped and formed with a flattened portion received within the incision of the socket and yieldingly engaging the opposite notch of the key.

In testimony whereof I affix my signature in presence of two witnesses.
